UNITED STATES PATENT OFFICE.

SAMUEL YOUNG, OF SAN FRANCISCO, CALIFORNIA.

DESIGN FOR A SMOKING SET.

Application filed May 18, 1928. Serial No. 26,734. Term of patent 7 years.

To all whom it may concern:

Be it known that I, SAMUEL YOUNG, a citizen of the United States, and a resident of the city and county of San Francisco, State of California, have invented a new, original, and ornamental Design for a Smoking Set, of which the following is a specification, reference being had to the accompanying drawings, forming part thereof.

I claim:

The ornamental design for a smoking set substantially as shown.

SAMUEL YOUNG.
